WILLIAM E. VAN DORN, OF PASADENA, CALIFORNIA

GONDOLA-CAR BODY

Application filed November 12, 1928. Serial No. 318,848.

The present invention has for its object to produce a metal gondola car body that shall be comparatively light and yet be strong and rugged and which can be made 5 at a lower cost than bodies of equal capacity as heretofore made.

In the ordinary steel gondola car the sides are usually made of flat metal sheets having reinforcing braces or struts riveted thereto 10 to give them the requisite stiffness to resist the lateral thrust of the load in the car. Thus each side consists of a considerable number of pieces that must be riveted together, thus making the cost of manufacture 15 much greater than if no such riveting together of parts were necessary. Viewed in one of its aspects, the present invention may be said to have for its object to make it possible to produce a gondola car body side 20 from a single plate or sheet, whether it be made in one piece or of a number of pieces arranged end to end, the material of the wall being simply folded to provide the necessary stiffening elements.

25 In carrying out my invention, as viewed in one of its aspects, the sides and ends of the body are made of metal panels in the form of thin plates or heavy sheets that have been folded upon themselves so as to provide 30 reinforcing ribs or webs, thus doing away with the need for separate braces or struts. The shaping of the panels may therefore be effected by a cold process and without stretching the metal to reduce its cross-section 35 in the fashioning of the stiffening elements. The ends of the side walls, for example, may be flanged over and secured to the marginal portions of the end walls, thus completing the shell without the use of 40 corner posts or framework. The bottom may be stiffened by means of a comparatively light frame to which the lower marginal portions of the end and side walls are fastened, and upon which floor stringers may 45 rest. The body is then completed by adding a rim or cap which overlies the upper edges of the side and end walls.

The folds in the side walls are preferably 50 so located as to produce strengthening ribs or webs extending diagonally from top to

bottom, adjacent ribs or webs being inclined in opposite directions. In other words, by placing these ribs or webs so that the upper end of each is near the upper end of an adjacent rib or web while the lower end is 55 near the lower end of another adjacent rib or web, there will be an arrangement of ribs or webs zigzagging throughout the length of the sheet or side to give a truss-like effect.

Therefore, viewed in one of its aspects, the 60 present invention may be said to have for its object to produce a side wall for a gondola car body, which wall shall consist of a comparatively light metal sheet or plate folded to produce ribs or webs so disposed as to 65 transform the sheet or plate into a truss.

The various features of novelty whereby 70 my invention is characterized will herein-after be pointed out with particularity in the claims; but, for a full understanding of my 70 invention and of its objects and advantages, reference may be had to the following detailed description taken in connection with the accompanying drawings, wherein:

Figure 1 is an end view of a car body 75 made in accordance with my invention; Fig. 2 is a transverse vertical section; Fig. 3 is a longitudinal vertical section; Fig. 4 is a side elevation of one end of the body; Fig. 5 is a view of the body partly in top plan and partly in section, the section being on line 80 5-5 of Fig. 3; Fig. 6 is a section on line 6-6 of Fig. 1; and Fig. 7 is a section, on an enlarged scale, on line 7-7 of Fig. 1.

Referring to the drawings, A and B represent 85 the two end walls and C and D the two side walls of a gondola car body of any usual or preferred size and shape. These walls are made of light plates or heavy 90 sheets and each may consist of one or more pieces, as desired. In the arrangement shown, each end wall is in the form of a single sheet or panel, bent or folded to produce three parallel trough-like ribs 1 extending from one end to the other. The side 95 walls are shown as taking the form of panels folded on diagonal lines zigzagging across the sheet or panel from one end of the car body to the other. The method of folding or bending adopted serves to divide the face 100

of the panel into approximately triangular areas lying in two parallel planes separated from each other; these areas being joined by webs extending transversely to said planes. The triangular inner sections 2 are positioned with their bases at the bottom, while the outer sections 3 have their bases at the top and their narrow ends at the bottom. The connecting webs 4 between the inner and outer sections are arranged at right angles to the plane of the sheet and zigzag across the side wall, from end to end, to transform the wall into a truss. It will be seen that an entire side wall could be made of the single piece whose original length would be equal to the final length of the wall plus an added length equal to the combined widths of the stiffening or reinforcing ribs.

20 End and side walls are connected together by suitably flanging them so that they will overlap and permit riveted or other joints to be made. In the arrangement shown, the side walls C and D are provided at their ends with flanges 5 that extend over and engage with comparatively narrow marginal portions along the ends of the end walls. Since the ribs in the end walls do not vanish at the ends of such walls, the material between the ends of the ribs may be gradually raised, as indicated at 6 in Figs. 5 and 7; thus forming with the end portions of the ribs continuous surfaces against which the flanges 5 bear.

35 A light floor supporting frame may be arranged in the bottom of the shell formed by the end and side walls. In the arrangement shown, there is a frame 7 of angle iron; the frame having vertical flanges lying against the inner faces of the end and side walls and riveted or otherwise secured to such walls, and having also inwardly-directed horizontal flanges. Suitable floor stringers 8 extend longitudinally of the body and are supported on the horizontal flanges 40 of the frame 7. Suitable flooring boards 9 are laid on the stringers.

45 Around the top of the car body is a cap or rim 10 in the form of an inverted trough or channel having one wide side wall and one narrow side wall. The long side wall fits against the inner faces of the end and side walls of the body and is riveted or otherwise secured to such walls. The corners of the cap or rim may be reinforced by means 50 of short auxiliary cap sections 11 overlying the same.

60 If desired, the upper portions of the side wall sections that lie outwardly from and parallel with the normal plane of the sheet may be gradually bent inward, as indicated at 12; so that a substantially continuous riveted joint may be made between each side wall and the overlying cap or rim.

65 It will be seen that the outer triangular

side wall sections 3, with the corresponding webs 4, form posts increasing in width from the bottom toward the top. If the lower ends of these posts can be rigidly held they will prevent any portion of the side walls 70 from swinging out at the top. I have therefore provided means for rigidly anchoring the lower ends of these posts to the cross beams on which the car body rests. These beams, of which two are shown at 13, are so 75 placed that each lies below the lower ends of the corresponding posts on opposite sides of the body. A stirrup 14 fits over each end of each beam and over the lower end of the corresponding post, being riveted or otherwise rigidly fastened to both the beam and the post. Each post is therefore firmly anchored at its lower end and, spreading fanwise toward the top of the side wall, 80 rigidly holds the side wall against outward 85 displacement, at the top or elsewhere, under pressure from within the car body.

It will thus be seen that I have produced a simple and novel gondola car body from a few light and simple but extremely stiff 90 panels, that is light metal plates or metal sheets; making it possible to dispense with separate reinforcing means in the form of struts or the like. Therefore such a body, although strong and rugged, will be light in 95 weight and may be manufactured at a low cost.

100 While I have illustrated and described with particularity only a single preferred form of my invention, I do not desire to be limited to the exact structural details thus illustrated and described; but intend to cover all forms and arrangements which come within the definitions of my invention constituting the appended claims.

105 I claim:

1. A frameless gondola car body comprising end and side walls of a single thickness composed of metal panels shaped to overlap at the four corners, and the overlapping portions of the panels being secured together, the end panels being folded upon themselves to produce stiffening ribs, the side panels being folded to produce therein vertical stiffening ribs, stirrups fixed to the lower ends of said vertical ribs, and transverse floor beams extending between and secured to corresponding stirrups on opposite sides of the body.

110 2. A frameless gondola car body comprising end and side walls of a single thickness composed of metal panels shaped to overlap at the four corners, and the overlapping portions of the panels being secured together, the end panels being folded upon themselves to produce horizontal stiffening ribs, the side panels being folded to produce vertical stiffening ribs, and said ribbed panels being stiff enough to give to the car body 115 the required stiffness.

3. A side wall of a gondola car body made of sheet metal folded upon itself to produce diagonal stiffening webs extending from the top to the bottom, adjacent webs being inclined in opposite directions to give a truss effect to the wall.
4. A gondola car body having metal side walls folded to produce sections generally triangular in shape lying in parallel inner and outer planes spaced apart from each other and connected together by webs transverse to said planes, said sections being so disposed that sections with the narrow ends at the top alternate with sections having their narrow ends at the bottom, transverse beams underneath the body in registration with the latter narrow ends, and stirrups fixed to said beams and each embracing and fixed to the adjacent webs and intervening flat portion of the corresponding side wall.
5. A frameless gondola car body comprising end and side walls of a single thickness composed of metal panels, means for securing said panels together at the four corners, the end panels being folded upon themselves to produce horizontal stiffening ribs, and the metal of the panels forming the side walls being folded to produce diagonal stiffening webs extending from the top to the bottom, adjacent webs being inclined in opposite directions to give a truss effect to the side walls.
6. A frameless gondola car body comprising end and side walls of a single thickness composed of metal panels shaped to overlap at the four corners, and the overlapping portions of the panels being secured together, the end panels being folded upon themselves to produce horizontal stiffness and the side panels being folded to produce vertical stiffness.
7. A frameless gondola car body having end and side walls made of metal panels folded to produce stiffening means therein transverse to their respective planes, the ends of the side walls at each corner being secured to the marginal portions of the adjacent end walls.
8. A frameless gondola car body comprising end and side walls composed of metal panels shaped to overlap and be secured together at the four corners, the end panels being folded upon themselves to produce horizontal stiffening means, the side panels being folded to produce vertical stiffening means, stirrups fixed to the lower ends of said vertical stiffening means, and transverse floor beams extending between and secured to corresponding stirrups on opposite sides of the body.

In testimony whereof I sign this specification.

WILLIAM E. VAN DORN.
